(57) **CLAIM**

The ornamental design for a burner controller, as shown and described.

DESCRIPTION

FIG. 1 is a perspective view of a burner control of the present invention;

FIG. 2 is a front side view of the burner control of FIG. 1;
FIG. 3 is a right side view of the burner control of FIG. 1;
FIG. 4 is a left side view of the burner control of FIG. 1;
FIG. 5 is a top side view of the burner control of FIG. 1; and,
FIG. 6 is a bottom side view of the burner control of FIG. 1. The portions illustrated in broken lines on the figures are for illustrative purposes only and form no part of the claimed design.
